SEWAGE SEPTIC TANK

Terrell D. Piotrowski, 103 Pamela Drive,
Athens, Ga. 30601

Filed Apr. 10, 1973, Ser. No. 349,822

Term of patent 14 years

Int. Cl. D23—01

U.S. Cl. D23—2

FIG. 2

FIG. 1

FIG. 3

FIG. 4

FIG. 1 is a top plan view of a sewage septic tank embodying my new design;

FIG. 2 is a side elevational view;

FIG. 3 is a bottom view; and

FIG. 4 is an end elevational view.

The characteristic feature of my design resides in the specific configuration of the ends of the sewage septic tank as shown in FIG. 4.

I claim:

The ornamental design for a sewage septic tank, as shown and described.
